UNITED STATES PATENT OFFICE.

JOHN JAMES BISHOP HARRIS, OF BROADHEATH, ENGLAND, ASSIGNOR, BY MESNE ASSIGNMENTS, TO WOOD NEWSPAPER MACHINERY CORPORATION, OF NEW YORK, N. Y., A CORPORATION OF VIRGINIA.

STEREOTYPER'S MATRIX AND VERTICAL MOLD FOR CASTING STEREOTYPE-PLATES FROM IT.

1,313,632.

Specification of Letters Patent.

Patented Aug. 19, 1919.

Application filed January 9, 1913, Serial No. 740,951. Renewed January 14, 1919. Serial No. 271,163.

To all whom it may concern:

Be it known that I, JOHN JAMES BISHOP HARRIS, a subject of the King of the United Kingdom of Great Britain and Ireland, residing at Linotype and Machinery Works, Broadheath, in the county of Chester, England, have invented new and useful Improvements in Stereotypers' Matrices and Vertical Molds for Casting Stereotype-
10 Plates from Them, of which the following is a specification.

In some vertical molds for casting curved stereotyped plates, so arranged that the molten metal is poured downward into them
15 through their open tops, the top margin of the matrix is safeguarded from the metal by a metal guard attached to the matrix clamping members of which there is one on each side of the matrix supporting member
20 of the mold, and which guard fits over the said margin and extends downward as far as the top bolster of the matrix, this bolster projecting into the mold beyond the said guard. Consequently, this guard
25 leaves the bolster exposed to the impact of the falling stream of metal. As the latter is poured from a point over the median vertical line of the mold, it strikes the middle of the bolster, and lastly, the middle of the
30 matrix. The impact of the metal upon the bolster and matrix makes both gradually creep down the matrix holding members, thereby (seeing that the bottom of the matrix is prevented by the bottom of
35 the mold from creeping downward) forming a projection on the casting face of the matrix. This projection projects into the mold far enough to spoil all the stereotype plates subsequently cast while it is there.

40 The present invention consists in means for preventing the said creeping. These means are illustrated in the accompanying drawings in which—

Figure 1 is a sectional elevation of a
45 chase, form, and flong illustrating the formation of the improvement in the matrix.

Fig. 2 is a sectional elevation through a vertical mold showing the matrix guarded from being made to creep; and, Fig. 3 is a
50 similar view, enlarged, of a modification.

Referring more particularly to Fig. 1, the improved matrix 1 has three angled shoulders 2, 3, 4 between its casting face

5 and its top margin 6. To properly produce these shoulders 2, 3, 4, the corresponding end 7 of the chase is for the major part, higher than the top of the form 8, and between this higher part and the form, there is a sink 9 in which the top bolster 10 of the matrix is made.

Referring to Fig. 2, 11 is the usual mold in which the stereotype plates are cast between 12, the convex member and 13, the concave member. It is the latter that has the matrix carrying members above mentioned thereby constituting it the matrix supporting member. 14 is a recess formed in the upper portion of the concave face of the member 13. This recess extends from one side to the other of the said member 70 to receive the entire top margin of the matrix, and may, as shown, be continued as far as its top. The object of this recess is to produce a shoulder 15 upon which the shoulder 4 of the matrix can bed. 16 is 75 the usual guard which, fitting over the top margin 6 of the matrix and down to its top bolster 10, holds the matrix shoulder 4 bedded down upon the shoulder 15 and is, therefore, nearly flush with the bolster. 80 Obviously, when its bottom edge is vertically flush with the moldward projection of the bolster 10, the main body of the falling metal will be shot off in the direction of the mold member 12, and thereby prevented 85 from striking the bolster. The impact of the metal upon the bolster 10 and the matrix below it, cannot cause the creeping above mentioned, for the reason that the shoulder 90 15 keeps the bolster 10 in its normal position and thereby prevents the matrix below it being made to project into the mold 11.

The invention includes the combination of a guard 160, Fig. 3, a concave member 130 and convex member 120, as used heretofore, *i. e.*, not having the recess 14 and consequent shoulder 15; and a matrix of any contour in respect of its top bolster, margin, or shoulders.

Although I have illustrated and described 100 only two forms of the invention, I am aware of the fact that many other modifications can be made therein without departing from the scope of the invention as expressed in the claims. Therefore, I do not wish to be 105 limited to all the details of construction

herein shown and described, but what I do claim is:—

1. As an article of manufacture, a vertical stereotype mold having a matrix provided with a top bolster and a guard arranged in position in the mouth of the mold to engage said bolster and direct the falling metal from the top side of said bolster as the metal descends in the mold.
- 10 2. As an article of manufacture, a stereotype mold having an open mouth at the top and provided with a matrix having a projecting bolster near the top thereof, a guard in the mouth of the mold resting over said bolster and having means for directing the falling metal away from the bolster, the wall of said mold having means for preventing the bolster from descending in the mold.
- 20 3. As an article of manufacture, a stereotype mold provided with a matrix therein having a bolster and a top margin, the top of said mold being provided with a projection behind the bolster for preventing the bolster being forced down along the mold wall by the descent of metal upon its outer face.
- 30 4. As an article of manufacture, a stereotype mold having an inwardly projecting shoulder in position to engage under the top shoulder of the matrix for preventing the descent of the matrix in the mold.
- 35 5. As an article of manufacture, a curved stereotype mold having the convex member thereof provided with a square shoulder projecting toward the matrix in position to en-

gage the bolster thereof and hold the same rigidly.

6. The combination with a stereotype mold having a recess in the pouring mouth thereof and provided with a square shoulder projecting inwardly at the bottom of said recess, of a matrix therefor provided with an inset top margin for fitting in said recess and with a bolster extending inwardly from the bottom of said margin, then downwardly 45 and outwardly at the bottom to form a top shoulder in position to rest on said shoulder.

7. The combination with a stereotype mold having a mold cavity at the bottom, a recess in the pouring mouth depressed beyond the 50 surface of said cavity and a sharp shoulder at the bottom of said recess, of a matrix therefor having three angled shoulders, the middle one of which registers with the shoulder on the mold and provided with a 55 top margin off-set from the main surface to the matrix to fit in said recess.

8. As an article of manufacture, a stereotype matrix having a top margin offset into a different plane from that of the body of the matrix, a bolster connected to this top margin by a pair of reverse shoulders and connected with the casting face by a third shoulder.

In witness whereof I have hereunto set my hand in the presence of two witnesses.

JOHN JAMES BISHOP HARRIS.
